TENSIONING DEVICE FOR STORM WINDOWS

Walter M. Krantz, Ferndale, Mich.

Application June 29, 1949, Serial No. 101,980

2 Claims. (Cl. 20—55)

1

This invention relates to storm windows and more particularly to combination storm windows wherein glazed and screened sash are removably positioned in mounting frames which in turn are positioned near or on dwelling house window openings to provide insulating window closures with respect thereto.

The principal object of the invention is the provision of a simple and inexpensive device for automatically tensioning the sash of a combination storm window with respect to the frame thereof.

A further object of the invention is the provision of a storm window sash having a channel in the edge thereof, an opening formed in said sash in communication with said channel and means in said channel registering with said opening for yieldingly increasing the effective thickness of the said sash whereby the same may be tightly fitted in a storm window frame.

A still further object of the invention is the provision of a storm sash having a channel in the edge thereof and an opening in said sash in communication with said channel and a ball in said channel in registry with said opening and extending partially therethrough, and means in the said channel for yieldingly holding the said ball in the said opening whereby the same may be tightly fitted in a storm window frame.

The storm sash tensioning means shown and described herein comprises a simple and efficient device formed in combination with a storm sash having a longitudinally extending channel in the edges thereof for increasing the effective width of the sash to enable the same to be self-supporting and self-sealing in a channeled frame in which it may be positioned so that a weather-tight seal is obtained by the said sash and said frame.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a fragmentary view of a portion of a storm sash frame and sash therein.

Figure 2 is a vertical section on line 2—2 of Figure 1.

Figure 3 is a horizontal section on line 3—3 of Figure 2.

2

Figure 4 is an enlarged detail of the tensioning means.

Figure 5 is a top plan view taken on line 5—5 of Figure 4.

5 By referring to the drawings and Figures 1, 2 and 3 in particular it will be seen that a storm sash frame 10 has been disclosed which is adapted to be positioned in or on a window opening and which has a pair of spaced flanges 11 and 12 thereon which define a channel 13 for the reception of a storm sash 14 which in turn has a channel 15 formed in its marginal edge. The storm sash 14 includes a panel of glazing materials 16 secured in the sash 14 by metal spline 17 as is customary in the art or as shown in my Patent No. 2,505,553. The two peripherally extending flanges formed by said channel 15 on the edge of the sash 14 are received between said flanges 11 and 12. As appears in the drawings, the flanges 11 and 12 are so spaced that the sash 14 is received snugly therebetween but a slight spacing is provided by which binding or seizing is positively prevented. However, this spacing, which is common in storm window practice, while necessary to prevent seizing or binding, normally permits leakage of air around the sash 14 and thus partially defeats the purpose of the storm window since it detracts from the insulation value thereof.

10 The present invention relates to the forming of one or more openings 18 in the sash and establishing communication with the channel 15 therein and positioning a ball 19 partially through the opening 18 so that a portion of the ball 19 extends beyond the plane of the sash 14 and thereby increases the effective width of the sash 14 at this point. A leaf spring 20 is positioned between the innermost portion of the ball 19 and the part of the sash 14 defining the other side of the channel 15 so that it yieldably positions the ball 19 in the opening 18. The ends of the leaf spring 20 are sharpened as at 21—21 so that they dig into the material of the sash 14 and thereby locate the leaf spring 20 with respect to the ball 19. As will be evident from the drawing, the ball 19 will be of a diameter slightly larger than the diameter of the opening 18 and yet it is sufficiently small that it will extend through said opening and slightly beyond the outer surface of the flange 14 in which the opening 18 is located. The thickness of the flange 14 is likewise substantially less than one-half the diameter of the ball in order to make it possible for the ball to extend therethrough. The spacing of the inner surfaces of the flanges 11 and 12 with respect to the outer surfaces of the flanges 14 is great enough to permit the ready sliding of

the flanges 14 between but is sufficiently small that the ball 19 will engage the flange 11 and will by it be pressed against the spring 20. Alternately, locating means may include the construction disclosed in Figure 5 of the drawings wherein a small opening 22 is formed in a leaf spring 23 to partially engage a ball 24. Either of these constructions will efficiently position the ball 19 with respect to the opening 18 in the sash 14. It will be obvious that when one or more of these devices are positioned in the sash 14 and the sash 14 moved into engagement in the channel 13 of the frame 10, the sash will be securely and tightly positioned therein so as to insure a weather-tight closure with respect thereto.

It will be observed that the spring 20 holds the ball 19 firmly in the opening 18 so that the entire unit is self contained and will not come apart even when the sash is removed from the supporting frame. This is of advantage in assembling the structure and is of particular advantage wherever one of these units is used on an end of a sash which will be removed from the frame when the window is open.

It will thus be seen that the several objects of the invention are met by the tensioning device for storm windows disclosed herein.

Having thus described my invention, what I claim is:

1. In a storm window sash adapted for support between a pair of spaced, parallel frame flanges, the combination comprising: a pair of peripherally extending, spaced, parallel sash flanges adapted to be received between said frame flanges, and an opening through one of said sash flanges; a leaf spring element engaging the other sash flange at a point opposite said opening and having a portion thereof intermediate its ends positioned to intersect the projected axis of said opening; a ball of diameter larger than the diam-

5

eter of said opening but small enough that it will extend through said opening and beyond the sash flange containing said opening, the thickness of said sash flange being substantially less than one-half the diameter of said ball; said leaf spring being curved away from said other sash flange by such a distance that it engages said ball and holds it against the edges defining said opening.

10

2. In a storm window sash adapted for support between a pair of spaced, parallel frame flanges, the combination comprising: a pair of peripherally extending, spaced, parallel sash flanges adapted to be received between said frame flanges, and an opening through one of said sash flanges; a leaf spring element engaging the other sash flange at a point opposite said opening and so positioned that its midpoint is located on the projected axis of said opening; a ball of diameter larger than the diameter of said opening but small enough that it will extend through said opening and beyond the sash flange containing said opening, the thickness of said sash flange being substantially less than one-half the diameter of said ball; said leaf spring being curved away from said other sash flange by such a distance that it engages said ball and holds it against the edges defining said opening.
